UNITED STATES PATENT OFFICE.

DAVID LIPPY, OF MANSFIELD, OHIO, ASSIGNOR TO THE MANSFIELD CASH AND PACKAGE CARRIER CO., OF MANSFIELD, OHIO.

CASH-CARRIER.

SPECIFICATION forming part of Letters Patent No. 697,347, dated April 8, 1902.

Application filed December 24, 1901. Serial No. 87,071. (No model.)

To all whom it may concern:

Be it known that I, DAVID LIPPY, a citizen of the United States, residing at Mansfield, in the county of Richland and State of Ohio, ⁵⁵ 5 have invented certain new and useful Improvements in Cash-Carriers, of which the following is a specification.

My invention relates to improvements in car stops and retainers for store-service apparatus; and the objects of my invention are, first, to provide a means for stopping and retaining a car and holding the same in a vertical position; second, to construct the retainer to be released from the car without ⁶⁰ 15 causing any strain upon the propelling-wire; third, to make a cheap, durable, and efficient means for the purposes stated.

Figure 1 is a side elevation of the outstation of a double-wire grade-line cash-carrier, ²⁰ 20 showing my improved stop and retainer in position. Fig. 2 is a side view of the home station, having a pivoted lever for spreading the wires and showing also the stop and retainer attached to the same; and Fig. 3 is a ²⁵ 25 side view, on an enlarged scale, of the home-station mechanism with the stop and retainer. Fig. 4 is a top view showing more fully the construction of the stop and retainer.

In the drawings, A indicates the outstation ³⁰ 30 of a double-wire cash-carrier line of the class known as "upward-spread" apparatus. The upper wire is secured to a foot forming a part of the hollow case B, provided with rollers C and adapted to slide upon an inclined rod D.

³⁵ 35 E indicates a bifurcated clip which answers three purposes—first, to form a hinged connection with the horizontal bar forming the foot F of the outstation to allow the track-wire G to be placed at any angle required; ⁴⁰ 40 second, to form a clip to which is secured the track-wire; third, to form a guide and bearing for the spring bumper-bar H. The said bar is provided upon its outer end with the rubber bumper I and nut J, and the inner ⁴⁵ 45 end with the hollow sleeve K and rubber bumper L. A coil-spring M surrounds the rod H and has a bearing between the block or clip E and the sleeve K, forming a spring-cushion for the car N.

⁵⁰ 50 O indicates the car-retainer, which is composed of one piece of wire bent upon itself to

form two parallel bars P and P', which are surrounded by the cushioning-springs P'', two radiating bars Q and Q, two vertical bars R and R, and one horizontal bar S. The bar ⁵⁵ S is provided with a latch T, which is composed of a flat plate hinged loosely upon the horizontal bar. The lower end is provided with the vertical flange U. The loose end of the latch when in normal position rests upon ⁶⁰ the two parallel bars P and P'. The latch may be constructed of metal and the inner face of the vertical flange U covered with leather, or heavy leather may be used for its construction. ⁶⁵

V and V indicate wire stops secured to or forming part of the latch. Their function is to prevent the latch from rising any higher than a given point to allow the upwardly-projecting pin W to pass under the latch when ⁷⁰ 70 the car enters the station. This description is fully illustrated in Figs. 1 and 3.

The retainer can be secured in suitable bearings in the sliding case B or the end of the pivoted lever X, which is used at the home ⁷⁵ 75 station, as shown in Fig. 2.

It will be readily seen that when a car enters the end of the retainer the pin W comes in contact with the inclined face of the latch T, raising the same, the car striking the ⁸⁰ rubber bumper L, compressing the spring M, which checks the velocity of the car, and before the car can rebound by the action of the spring the latch falls into its normal position, as shown in Fig. 1. A downward pull upon ⁸⁵ 85 the handle Y or lever Z raises the retainer off the pin W, allowing the car to be propelled up or down the grade.

I claim—

1. In a store-service apparatus, the combination of the hangers or brackets, the upper spring-buffers, the lower track-wires, and the foot, of the bifurcated clip hinged to said foot and holding one end of the lower track-wire, a spring buffer-bar guided in said clip, the inclined rod, the case mounted to slide thereon, and to rest normally on said clip, and the upper track-wire secured to said case, substantially as described. ⁹⁰ 95

2. In a store-service apparatus, the combination of the hangers or brackets, the upper spring-buffers, the lower track-wires, and the

foot, of the bifurcated clip hinged to said foot and holding one end of the lower track-wire, a spring buffer-bar guided in said clip, the inclined rod, the case mounted to slide thereon and to rest normally on said case, the upper track-wire secured to said case, and a car-retainer, a latch thereon, and cushioning-springs, all substantially as shown and described.

10 3. In a store-service apparatus, the combination of the hangers or brackets, the upper spring-buffers, the lower track-wires and the foot, of the bifurcated clip hinged to said foot and holding one end of the lower track-wire, a

spring buffer-bar guided in said clip, the inclined rod, the case mounted to slide thereon and to rest normally on said clip, the upper track-wire secured to said case, a car-retainer, a latch thereon, cushioning-springs, and stops carried by said latch, all substantially as described. 15

In testimony whereof I affix my signature in presence of two witnesses.

DAVID LIPPY.
